(57) **CLAIM**

The ornamental design for a tapered area light fixture, as shown and described.

DESCRIPTION

FIG. 1 is a top perspective view of a first embodiment of a tapered area light fixture, showing the new design; FIG. 2 is a bottom perspective view of the first embodiment thereof;

FIG. 3 is a front elevational view of the first embodiment thereof;

FIG. 4 is a rear elevational view of the first embodiment thereof;

FIG. 5 is a right-side elevational of the first embodiment view thereof;

FIG. 6 is a left-side elevational of the first embodiment view thereof;

FIG. 7 is a top plan view of the first embodiment thereof; FIG. 8 is a bottom plan view of the first embodiment thereof; FIG. 9 is a top perspective view of a second embodiment of the tapered area light fixture, showing the new design;

FIG. 10 is a bottom perspective view of the second embodiment thereof;

FIG. 11 is a front elevational view of the second embodiment thereof;

FIG. 12 is a rear elevational view of the second embodiment thereof;

FIG. 13 is a right-side elevational view of the second embodiment thereof;

FIG. 14 is a left-side elevational view of the second embodiment thereof;

FIG. 15 is a top plan view of the second embodiment thereof; and,

FIG. 16 is a bottom plan view of the second embodiment thereof.

The broken lines illustrate portions of the tapered area light fixture that form no part of the claimed design.
